UNITED STATES PATENT OFFICE

FRANK G. HARRISON, OF MASSILLON, OHIO, ASSIGNOR TO THE SPUN STEEL CORPORATION, OF CANTON, OHIO, A CORPORATION OF OHIO

PULLEY

Application filed May 19, 1928. Serial No. 279,110.

My invention relates to adjustable V-pulleys and the like which may include an inner cylindric body having an outwardly extending peripheral flange at a suitable angle to the body to form one side of a V-pulley groove, and a separate outer cylindric body seated upon the inner cylindric body and having an outwardly extending peripheral flange at a suitable angle to the body to form the other side of the V-pulley groove, and means for securing the inner and outer bodies and attached flanges in fixed relation with each other after their relative positions have been adjusted as desired.

More particularly my invention relates to adjustable V-pulleys whose inner and outer bodies are each made by pressing and spinning a blank disk or the like as set forth in the application of Reynold G. Nelson, for patent for Spun Metal Manufacture and Products, Serial No. 212,496, filed August 12, 1927.

The adjusting and securing means set forth in that prior application, have been found to be relatively expensive to manufacture, and the principal objects of the present improvements include the provision of an adjustable V-pulley as aforesaid, including simple and economical adjusting and securing means.

These and ancillary objects are attained in the present improvements as will be herein-after set forth in detail and claimed.

A preferred embodiment of the improvement is illustrated in the accompanying drawing forming part hereof, in which—

Figure 1 is an elevation view of an adjustable V-pulley embodying the present improvements;

Fig. 2, a view similar to Fig. 1 with one of the securing bolts removed;

Fig. 3, a fragmentary sectional view thereof as on line 3—3, Fig. 1;

Fig. 4, a longitudinal axial sectional view of the inner cylindric body and flange dis-

assembled from the remaining parts of the pulley; and

Fig. 5, a similar view of the outer cylindric body and flange.

Similar numerals refer to similar parts throughout the several views.

The improved adjustable V pulley indicated generally at 11 in Figs. 1 and 2 includes an inner cylindric body 12 provided at one end with an outwardly flaring peripheral flange 13 at a fixed angle with the cylindric body depending on the particular angulation of the V belt with which the pulley is intended to be operated.

The other end of the cylindric body 12 is preferably closed as by the circular end wall 14 provided with suitable apertures therein by which the pulley may be secured to a suitable hub, not shown.

An outer cylindric body 16 is slidable on the inner cylindric body and is provided at its end adjacent the flanged end of the inner cylindric body 12, with an outwardly flaring peripheral flange 17 at an angle to the outer body 16 reverse to that of the angle of the flange 13 to the inner body 12.

The face 18 of the flange 13 opposes the face 19 of the flange 17, and the faces 18 and 19 form a V groove for the pulley in which a V belt is adapted to ride and turn or be turned by the pulley; and for providing adequate gripping pressure on the sides of the V belt, the distance between the opposed faces of the pulley groove is adjustable by longitudinally sliding the outer cylindric tubular body 16 upon the inner cylindric cup body 12.

The improved means for securing the inner and outer bodies and their flanges at desired selective positions with respect to each other includes circumferentially spaced angled slots 20 in the outer cylindric body 16, and circumferentially spaced preferably square angular apertures 21 in the inner cylindric body 12, and bolts 22 each having a head 23 and a shank including a preferably square angular portion 24 adjacent the head and an outer threaded end 25 for receiving the usual nut 26.

The square angular portion 24 of the shank of each bolt fits in one of the square angular

5 apertures 21, and extends outwardly through one of the slots with the flat sides of the shank fitting the sides of the slot, a sufficient distance to provide a cam guide for the slot, but not beyond the outer surface of the outer body.

10 The sides of the square apertures 21 are preferably alined with and register with the sides of the slots 20; and in any event, the flat side portion of the shank which enters the slot will correspond in width thereto, so that the flat sides of the shank may be continuous through the aperture and into the slot.

15 A washer 27 is provided for each bolt 22 and preferably includes a tang 28 for extending into the slot 20.

20 Simple and efficient securing means are thus provided, which are relatively inexpensive, and which do not damage the material of either the inner or outer cylindric bodies.

25 I claim:

1. An adjustable pulley and the like including an inner tubular body, an outer tubular body slidable upon the inner body, and means for securing the bodies at any desired position of adjustment with respect to each other, including an angled slot in one of the bodies, an angular aperture in the other body, and clamping means including a bolt having a shank provided with an angular portion fitting the angular aperture, and a flat side portion fitting the width of the slot.

2. An adjustable V pulley and the like including an inner tubular body, an outer tubular body slidable upon the inner body, and means for securing the bodies at any desired position of adjustment with respect to each other, including circumferentially spaced angled slots in one of the bodies, and similar circumferentially spaced angular apertures in the other body, and clamping means for each aperture and slot including a bolt having a shank provided with an angular portion fitting the angular aperture and a flat side portion fitting the width of the slot.

45 In testimony that I claim the above, I have hereunto subscribed my name.

FRANK G. HARRISON.
